NARROW EMBROIDERED FABRIC

Nathan Berlin, 4 Sheffield Road, Great Neck, N.Y.

Filed Nov. 23, 1959, Ser. No. 58,438

Term of patent 3½ years

(Cl. D3—9)

The figure is a plan view of a narrow embroidered fabric, showing my new design.

The fabric is shown against a dark background so as to bring out more clearly the details thereof.

I claim:

The ornamental design for a narrow embroidered fabric, substantially as shown and described.
